(57) **CLAIM**

The ornamental design for a winch ring, as shown.

DESCRIPTION

FIG. 1 is a left front perspective view of a winch ring showing the claimed design;

FIG. 2 is a front plan view thereof;

FIG. 3 is a real plan view thereof;

FIG. 4 is a top plan view thereof;

FIG. 5 is a bottom plan view thereof;

FIG. 6 is a left side view thereof;

FIG. 7 is a right side view thereof;

FIG. 8 is a section view taken along line 8-8 shown in FIG. 2 thereof;

FIG. 9 is a left front perspective view of another embodiment of the winch ring showing the claimed design;

FIG. 10 is a front plan view thereof;

FIG. 11 is a real plan view thereof;

FIG. 12 is a top plan view thereof;

FIG. 13 is a bottom plan view thereof;

FIG. 14 is a left side view thereof;

FIG. 15 is a right side view thereof; and,

FIG. 16 is a section view taken along line 16-16 shown in FIG. 10 thereof.
